MEANS FOR PRODUCING FUZZY OR IMITATION FIBER YARN FROM CONTINUOUS FILAMENT YARNS

Vasser Woolley, Atlanta, Ga., assignor to Seydel Woolley & Company, Atlanta, Ga., a copartnership of Georgia

Application January 18, 1939, Serial No. 251,505

6 Claims. (Cl. 57—2)

The production of artificial silk or rayon and similar yarn has developed extensively in the past few years. The ordinary continuous filament yarn consisting of a bundle of minute fibers however is smooth and too shiny for some purposes. In order to overcome the objection to the shiny surface it has been proposed to break up the continuous filaments into short lengths and then spin the short lengths in a manner similar to the spinning of other short fibers. It has also been proposed to roughen the surface of the continuous filaments sufficiently to produce a fuzzy or imitation short-fiber yarn. The first method, however, involves a much greater expense and difficulty in the production of the finished yarn.

My invention accordingly is directed to the roughening of the surface of the continuous filaments without materially weakening them or breaking up the bundle into short lengths. German patent to Schulke No. 342,223 discloses a process of roughening by abrasion. I have utilized this principle in a special manner so that the continuous filament yarn is passed over or through an abrasive guide which is vibrated as the yarn passes over, through or across it.

One object of the invention is to produce a yarn that is of uniform texture, good in appearance and of good breaking strength.

Another object is to provide a method that is readily controlled.

Fig. 1 shows one form of mechanism for treating continuous filament yarn in accordance with my invention.

Fig. 2 shows another means for vibrating the abrasive across which the yarn passes as it is being twisted.

Fig. 3 shows a third method of vibrating an abrasive guide for the yarn.

Fig. 4 shows still another method of vibrating an abrasive. It should be understood, however, that the roughening of the yarn as illustrated is greatly exaggerated.

Fig. 5 is a diagrammatic view of another method of abrading rayon filaments.

The invention as shown in Fig. 1 is applied to a conventional type of ring twisting apparatus in which the yarn 7 is wound upon a spindle 8 driven in the usual manner. The untreated yarn passes between feed rolls 9 and 10 and through a guide 11 and a traveler 12 mounted on a ring support 13 which is actuated in the usual manner.

The balloon guide 11 is provided on its interior with an abrasive surface 14. This surface may be formed by roughening the surface of the guide

or by applying an abrasive such as carborundum, emery or the like. This guide is vibrated laterally at high speed as the yarn passes through it so as to alternately engage the yarn on opposite sides as it twists in passing to the traveler ring. This vibration may be effected in any suitable manner, as for instance, by means of the crank 15 and connecting rod 16. It will be seen that any suitable form of twisting machine may be readily modified to provide for the roughening action desired by simply substituting a suitable abrasive guide and providing means for vibrating the guide to and fro.

In the form shown in Fig. 2, the abrasive member 17 is vibrated by electromagnet 18 having a core 19. Such a magnet may be actuated by an alternating current or by using a direct current with an interrupter and a spring 20. In this form of construction, the abrasive by the vibration is moved diagonally with respect to the travel of the yarn so that there are transverse and longitudinal components of the abrasive action.

In the form shown in Fig. 3, the abrasive guide ring 21 is vibrated laterally by a cam 22 and a spring 23, the guide ring having a shaft 24 and 25 a roller 25 which engages the cam. The cam is rotated at a high rate of speed so as to vibrate the guide 21 as the yarn passes through it.

In the form shown in Fig. 4, the yarn is drawn over a support or guide 26 and acted upon by a roller or wheel 27 having an abrasive surface. This wheel is rotated in any suitable manner and is vibrated by means of a striker 28 which rotates against a roller 29 on the end of a rod 30 which carries the wheel. A spring 31 presses the rod 30 and the wheel in one direction and the striker moves it in the opposite direction. The striker being rotated at high speed vibrates the abrasive roller back and forth so that it engages the yarn at intervals as the yarn travels across the guide 26.

In Fig. 5, I have shown diagrammatically an abrading member 35 actuated by an electric motor 36 such as is used in an electric razor. This is applied between the feed rolls 9, 10 and the guide 37 where the yarn is twisting. A guide such as 11 or 21 may be vibrated in the same manner. The effect of the vibration seems to be to break up the periodic oscillations set up in the yarn. As a result some of the filaments are roughened and a fuzzy appearance is obtained without undue weakening of the yarn.

It will be seen that in each case the raw yarn or continuous filament comes in contact with an abrasive which is vibrating at a rapid rate,

thus causing quick, short, positive strokes by the abrasive or cutting elements across the filament resulting in a better roughening.

5 The rate of vibration or number of strokes of the abrasive per minute may be varied as well as the length of the stroke so as to modify the action of the abrasive in any suitable manner. By controlling the speed of movement of the yarn and the tension of the yarn various results 10 15 20 25 30 35 40 45 50 55 60 65 70 75 80 85 90 95 100 105 110 115 120 125 130 135 140 145 150 155 160 165 170 175 180 185 190 195 200 205 210 215 220 225 230 235 240 245 250 255 260 265 270 275 280 285 290 295 300 305 310 315 320 325 330 335 340 345 350 355 360 365 370 375 380 385 390 395 400 405 410 415 420 425 430 435 440 445 450 455 460 465 470 475 480 485 490 495 500 505 510 515 520 525 530 535 540 545 550 555 560 565 570 575 580 585 590 595 600 605 610 615 620 625 630 635 640 645 650 655 660 665 670 675 680 685 690 695 700 705 710 715 720 725 730 735 740 745 750 755 760 765 770 775 780 785 790 795 800 805 810 815 820 825 830 835 840 845 850 855 860 865 870 875 880 885 890 895 900 905 910 915 920 925 930 935 940 945 950 955 960 965 970 975 980 985 990 995 1000

10 It will be understood that I have illustrated the various forms of vibrating devices as suggestive of the principle of the invention. I have found that the action of a vibrating abrasive

15 is superior to that of a stationary abrasive in that a continually changing surface of abrasive is presented to the yarn as the yarn travels and is twisted. A stationary abrasive tends to become clogged and ineffective and in some cases 20 tends to tear and destroy the filament or strands of the filament. While a somewhat irregular fuzziness is desired, the irregularity should not be so great as to damage the continuity of the main body of the yarn. It is obvious also that 25 any action which results in the breaking of a bundle of filaments is highly objectionable. By my invention such difficulties are eliminated.

Although the idea of vibrating the abrasive seems quite simple, I have found very marked 30 improvements resulting from its use. For instance yarn was treated by passing it through a guide provided with an emery abrasive about 100 to 120 grit. In one set of tests the guide was vibrated rapidly by short strokes longitudinally of the yarn, e. g., .1" to .2" at the rate of say 7000 to 14000 strokes per minute, such for instance as may be produced by an electric razor motor. In the other set of tests the guide was held stationary.

55 60 65 70 75 80 85 90 95 100 105 110 115 120 125 130 135 140 145 150 155 160 165 170 175 180 185 190 195 200 205 210 215 220 225 230 235 240 245 250 255 260 265 270 275 280 285 290 295 300 305 310 315 320 325 330 335 340 345 350 355 360 365 370 375 380 385 390 395 400 405 410 415 420 425 430 435 440 445 450 455 460 465 470 475 480 485 490 495 500 505 510 515 520 525 530 535 540 545 550 555 560 565 570 575 580 585 590 595 600 605 610 615 620 625 630 635 640 645 650 655 660 665 670 675 680 685 690 695 700 705 710 715 720 725 730 735 740 745 750 755 760 765 770 775 780 785 790 795 800 805 810 815 820 825 830 835 840 845 850 855 860 865 870 875 880 885 890 895 900 905 910 915 920 925 930 935 940 945 950 955 960 965 970 975 980 985 990 995 1000

desirable that at least some or most of the filaments of the usual raw bundle be scratched or broken at intervals but that the action be such that the interruptions in the various filaments be distributed at irregular intervals along the 5 length of the yarn. Some filaments may be broken at intervals of say one or two inches, and others at intervals of every two or three inches. Some filaments may not be broken for several inches. In this way it is possible to roughen 10 all or practically all of the filaments and still retain desirable strength in the finished twisted yarn and yet produce the desirable appearance of fuzziness.

I have used the term "rayon" to include artificial filamentary substances in general such as are used in the place of and with silk and other fibers. Some viscose filaments are so tough or hard that very little if any roughening can be accomplished with stationary abrasives. Treatment by my vibratory abrasive method however is quite effective. In fact this method may be employed successfully to give a fuzzy or nappy appearance to almost any relatively smooth yarn with a minimum reduction in strength. 25

I claim:

1. In a yarn machine, a guide for the yarn having an abrasive surface, means for vibrating the guide laterally of the yarn and intermittently engaging one side of lengths of the yarn and means for winding and twisting the yarn as it passes through said guide.

2. In a yarn machine, in combination, feed rollers adapted to receive yarn from a source of supply, a ring for twisting the yarn and a vibrator having an abrasive surface for intermittently and rapidly roughening the yarn simultaneously with the twisting.

3. Means for abrading a rayon filament yarn comprising an abrader vibrated over a distance 40 of the order of .1" to .2" at a rate of the order of several thousand strokes per minute and means for feeding twisting filaments past this abrader.

4. The method of roughening rayon yarn which comprises twisting a bundle of continuous filaments of rayon, feeding the bundle of filaments in a substantially straight line and while so feeding and twisting said bundle applying an abrasive to one side only of the bundle longitudinally thereof over a distance of the order of one 50 tenth to two tenths of an inch at the rate of the order of several thousand strokes per minute.

5. The method of treating a bundle of rayon filaments which comprises twisting the bundle and while the bundle is twisting applying an 55 abrasive action intermittently longitudinally of the bundle to that part of it which is twisting.

6. In a machine for producing roughened rayon-like yarn, the combination of means for feeding a bundle of substantially continuous filaments, means for twisting said bundle of filaments to form twisted yarn and means for intermittently and rapidly applying an abrasive to one side of the twisting yarn while the opposite side is free so as to roughen some of the filaments of the twisting yarn.

VASSER WOOLLEY.
